Primary Examiner—Cathron C. Brooks*Assistant Examiner*—Maurice Stevens(74) *Attorney, Agent, or Firm*—Calfee, Halter & Griswold LLP(57) **CLAIM**

We claim the ornamental design for a valve body, as shown and described.

DESCRIPTION

FIG. 1 is a perspective view of a valve body that is a first embodiment of the new design;

FIG. 2 is a top view of the valve body of FIG. 1;

FIG. 3 is a bottom view of the valve body of FIG. 1;

FIG. 4 is a left side view of the valve body of FIG. 1;

FIG. 5 is a front view of the valve body of FIG. 1;

FIG. 6 is a right side view of the valve body of FIG. 1; and,

FIG. 7 is a rear view of the valve body of FIG. 1.
